MULTIPLEX SOUND RECORDING AND REPRODUCING SYSTEM

Application filed September 13, 1927, Serial No. 219,217. Renewed April 20, 1931.

This invention relates to recording and reproducing sound, and more particularly to recording and reproducing simultaneously and in a single record, or concomitant records, sounds of a wide variety. It has been found that a single sound record, such for instance as a single record groove, or a single photographic record, cannot be used for the faithful recording and reproduction of sounds having widely varying characteristics, and particularly sounds that differ greatly in pitch. The difficulties may be visualized by considering the making and reproduction of an ordinary phonograph record. When the groove is initially cut, the cutting needle is actuated by a sound operated mechanism of some type or other; and it has been found very difficult, if not quite impossible, to accommodate that mechanism equally well to sound vibrations throughout the whole pitch range of audible sound. A needle actuating mechanism that responds accurately to sounds of a given pitch, or throughout a limited pitch range, is found not to respond so well to sounds of other pitches. And even the material in which a record groove is cut has an effect in the same direction, as it may resist lateral movement of the needle at relatively high velocity in a degree disproportionate to its resistance to such lateral movement at relatively lower velocity.

Thus a single groove record sometimes falls far short of having in it an audible representation of the large variety of sounds produced, for instance, from an orchestra. And furthermore, when the record comes to be reproduced, further difficulties of the same kind are introduced in the reproducing needle following the record groove, and also in the sound producing mechanism actuated by the needle. The sound producing mechanism has the same shortcomings that are found in the recording mechanism, responding best to certain pitch ranges, and less well to others; and, again, the reproducing needle, whose movements are opposed by the forces necessary to actuate the sound producing mechanism, is in many instances prevented from following the record groove faithfully. The sum total result is in many

instances a comparatively poor final reproduction of the sounds supposed to be reproduced.

And although a photographic sound record uses no needles and comprises few mechanical operating parts, the same general shortcomings are found in that system. Typically, such a system will involve, for recording, a microphone connected into the input circuit of an amplifying system, the output of which is used in some manner to vary the light which falls upon a traveling film. Although there may be no inertia or similar factors involved in the actual exposure of the film, and although light control or variation may respond with very perfect accuracy to the pulsating current coming from the amplifier outfit, yet in the amplifying system, and in the microphone itself, are usually found serious deficiencies in full response to a wide pitch range. For instance, the inertia and other characteristics of the microphone cause it to respond best to certain pitch ranges and less well to others. While it is comparatively easy to design and construct a microphone which will operate with satisfactory uniformity throughout a limited pitch range, it is practically impossible to construct a microphone that will respond with satisfactory uniformity throughout the whole audible pitch range. Likewise in the amplifying system there are certain elements which cannot be given uniform action throughout the audible pitch range, and this is particularly true of the transformers used in such amplifying systems. Transformers have been successfully constructed which will respond with fair uniformity throughout the middle portion of the audible range, but such transformers drop off in their efficiency as both ends of the audible pitch range are approached. Thus, such transformers, although great care is taken in their design and construction, do not accurately transmit sounds of widely varying characteristics.

While it is difficult, if not impossible, to design and construct the various elements of the foregoing systems to respond well and uniformly throughout the audible pitch range, it is comparatively easy to design and construct such elements so that they will re-

spond with satisfactory uniformity throughout a limited pitch range, and also so that, outside of that limited pitch range, they will drop off rather sharply in their efficiency. 5 By making use of these characteristics I have evolved a multiplex system of sound recording and reproduction that very effectively overcomes the difficulties heretofore encountered. I do this by providing a suitable number 10 of independently operating units, each unit, and the elements thereof, being designed, constructed and operated in such manner as to obtain a substantial uniformity of action throughout the limited pitch range 15 imposed upon that unit. I divide the audible pitch range into several limited ranges; then I provide a complete recording or reproducing unit for acting substantially exclusively within each such limited pitch range. For 20 instance, in a recording system using electrical amplifiers, the microphone, transformers and other elements in each unit are designed to have satisfactory uniform response and efficiency throughout the corresponding 25 limited pitch range. Then, because each such unit may be made comparatively poorly responsive to pitches outside that range, or because in practical operation each such unit is more or less shielded from sounds to which 30 it does not well respond, or because of both those things acting in conjunction, I obtain a final sound record in which the whole range of sounds is faithfully and accurately recorded and in which no distorted sounds are recorded because each recording unit has been 35 operating only as regards recordation of such sounds as it is capable of recording with substantially perfect faithfulness. And, preferably, each unit will make its own separate 40 record. Several records may be all contained upon a single record carrying element, as upon a single strip of film, or upon a single phonograph disk, or may be contained upon several different record carrying elements 45 which are operated synchronously. It is only necessary that the several records be concomitant; not that they be integrated or superimposed.

In carrying my invention into effect, it will 50 be understood that the absolute efficiencies of corresponding elements in the several units, or of the several units, need not be the same. For instance, the absolute efficiency of a microphone used for the lowest pitch range may 55 be quite different from the absolute efficiency of the microphone used in the unit for another pitch range. For, as long as the efficiency of each microphone is fairly uniform throughout its own limited range, the final 60 recording or reproduction may be made uniform throughout the whole range by introducing corrective factors which raise or lower the amount of energy, or amplification, in one or more of the units as a whole.

65 With this preliminary discussion of the

invention in mind, the invention will now be best understood from the following detailed description of typical forms of the system, reference for this purpose being had to the accompanying drawings, in which:

70 Fig. 1 is a diagram showing a recording system, according to my invention, utilizing electrical amplification, and making a multiple photographic record:

75 Fig. 2 is a diagram indicating a typical division of the audible pitch range into several limited ranges and showing efficiency curves hereinafter explained;

80 Fig. 4 is a diagram illustrating the making of a multiple mechanical sound record in accordance with my system;

85 Fig. 3 is a diagram showing a reproduction system for the multiple record made by the system of Fig. 1;

90 Fig. 5 is a diagram illustrating the reproduction of such a multiple record as shown in Fig. 4; and

95 Fig. 6 is a diagram illustrating how one of my multiplex records may be made from a sound record of ordinary type.

100 In Fig. 1 I indicate a plurality of microphones M, M₁, M₂, M₃ and M₄. Each of these microphones is connected into the input circuit and the first transformer L of an individual electrical amplifying system A, A₁, A₂, A₃, or A₄, and the output circuit 10 of each such amplifying system goes to some suitable light producing element, as for instance to a glow tube as indicated at 11, there being an individual glow tube for each amplifying unit A, A₁, etc. The response of the glow tube to the electrical pulsations will be understood without the necessity of any detail description, the light emitted by each tube varying in accordance with the pulsations. The images of the glow tube may then be thrown by lenses 12 upon a film or films. Typically I show all of the glow tube images being cast upon a single moving film F; resulting, upon development of the film, in a plurality of photographic records R, R₁, R₂, R₃ and R₄, each record corresponding to the pulsations that have been impressed upon the corresponding glow tube.

110 It will be understood that the use of a glow tube, as here shown, is merely typical, and that the particular kind of record made by such glow tube is merely typical of several other arrangements by which a photographic sound record may be made. My invention here is not concerned with the particular kind of record, but resides characteristically in the production and reproduction of a multiplex record in the manner described.

115 A typical amplifying system which I may use for my purposes will usually involve a number of amplifying tubes T, and transformers L, L¹, etc. Such an amplifying system may involve several tubes and several 120 transformers in each sound transmitting and 125

amplifying unit. Various methods of circuiting may be employed and need not here be described in detail, it being sufficient to note that the efficiency of such an amplifying unit, at varying vibration frequencies, is very largely dependent upon the efficiency of the transformers at those frequencies. Generally speaking, the amplification efficiency of a tube is fairly uniform throughout the audible range of sound, whereas that was not true of the efficiency of the transformer. And the first transformer in each unit, as the transformer designated "L" in the drawings, is the one most important to maintain at uniform efficiency.

Fig. 2 indicates diagrammatically typical efficiencies of transformers. In this diagram the audible range of frequency is shown in ordinate while efficiency is indicated in abscissa. The dotted line E may be taken as showing an efficiency curve for a transformer that has been designed and built to cover, as well as may be, the entire audible range. Full line curves e , e^1 , e^2 , e^3 , e^4 indicate typical efficiency curves of my individual transformers L and of the several amplifying systems A, A^1 , A^2 , etc. Each such transformer L, L^1 , etc., may be designed and built not only as to attain as high an efficiency as practical throughout the particular limited pitch range to which it applies, but also to obtain an efficiency as nearly uniform as may be throughout that range. Thus the transformers L, L^1 , etc., of the amplifying unit A are made to have a uniform high efficiency for the pitch range between say 50 and 300 vibrations per second; the transformers of amplifying unit A^1 have the same high uniform efficiency throughout a pitch range from 300 to 600 vibrations per second, and so on, as indicated in the diagram in Fig. 2. Furthermore, each of these transformers may be so designed and constructed that its efficiency may drop off rather sharply at or near the limits of the corresponding pitch range, so that each transformer, although fully responsive to vibrations within its corresponding pitch range will be comparatively unresponsive to vibrations outside its corresponding pitch range. Such a condition is indicated by the incipient drops at the ends of each of the curves e , e^1 , etc. And what I say of the characteristics of the transformer of the individual amplifying units, may also be true of the characteristics for the microphones of each of these units, and of each unit as a whole; each microphone being designed and constructed so as to have a uniform high efficiency within its corresponding pitch range; and may also have a decided efficiency drop at or near the limits of its pitch range. The factors which control design of such elements, such as transformers or microphones, to attain uniform high efficiency, within a limited range, are known to the art and need no specific setting out here.

But when all such elements have been so designed as to attain the characteristics desired in my system, it will in many cases be found that the absolute efficiency of the elements of one unit differs from the efficiency of the corresponding elements of another unit; and that, correspondingly, the over-all efficiency of one complete unit, including its microphone may be quite different from the over-all efficiency of another such unit. These absolute differences in efficiencies, however, may be easily compensated by proper control of each unit as a whole; for instance, by properly adjusting and controlling the ratio of amplification that takes place in one or more of the amplifying tubes. By such adjustment and control the several efficiency curves e , e^1 , etc., may be made to lie very nearly in a straight line across the diagram of Fig. 2, with a corresponding equality in efficiency of recordation of the several classes of sounds which are being handled by the several amplifying units.

To explain the use of my system for sound recording, let the recording of an orchestra be considered. In an orchestral production there are sounds ranging usually substantially to both limits of audibility. Preferably in recording orchestral music the several microphones M, M^1 , etc., will be placed each in the most advantageous position for taking the class of sounds to which its transmitting and amplifying unit is best adapted.

The classification of the microphones and the units being on the basis of pitch, it may be advantageous to some degree to arrange the instruments of an orchestra more or less in accord with their average pitch ranges; so that those of lowest pitch may be effectively grouped near microphone M, those of the next pitch range being grouped near microphone M^1 , and so on. Also, it may be desirable partially to shield the several microphones against sounds from instruments out of their respective pitch ranges; but such shielding cannot be carried too far, especially if the several units are very little responsive to pitches out of their respective selected pitch ranges, as thereby characteristic overtones of instruments might be too much lost in the record.

In Fig. 3 I show a system of reproduction corresponding to the record making system of Fig. 1. Here the record film F is illustrated passing before a number of sensitive elements S, S^1 , S^2 , S^3 , S^4 , to intercept light from suitable illuminants I falling upon the several records and passing through the records to affect the sensitive elements S, etc. These sensitive elements may be, for instance, photoelectric or selenium cells. Elements S are connected into the input circuit of the several amplifying systems A, A^1 , A^2 , A^3 , A^4 , which may be, and are illustrated as being, the same as those shown in Fig. 1. For sim-

plicity of illustration, the amplifying units, except unit A, are merely indicated in block on the diagram. The output circuits 10 of these several amplifying units then go, respectively, to the speakers H, H¹, H². The same controlling conditions of design and construction are observed in the reproducing units as in the record making units; and the same general results are achieved as before described. Just as in the record producing system all of the various sounds, regardless of their wide pitch range, are fully and faithfully recorded; here in the reproducing system all such sounds are faithfully and fully reproduced with a uniformity of results extending throughout the range of sounds.

In addition to the selective arrangements hereinbefore described, or in partial or substantially complete substitution therefor, other arrangements may be used in the system. For instance, around the secondary of the first transformer L an adjustable tuning resistance R may be used; or around the secondary of the transformer L¹ an adjustable tuning condenser C may be used. By proper adjustment of such elements the responsive range of an amplifying unit may be more or less concentrated within the selected limited pitch range, and the efficiency, and uniformity of efficiency, within that limited pitch range may be increased and fixed. And it may be well here to note that, although the efficiency of any one unit may not be quite uniform throughout its corresponding limited pitch range, that fact is not one which negatives the general results attained by my system. A slight drop off in efficiency toward the ends of the limited range is not of so great disadvantage as the shortcomings which my system is intended to overcome. And, furthermore at points near the limits of the several ranges each unit is to a certain extent reinforced in its action by the unit or units of the pitch ranges adjacent. As indicated by the curves in Fig. 2, although, outside its own pitch range, each unit may drop off rather sharply in efficiency, it will, unless completely shielded from sounds except in its own pitch range, add somewhat to the action of an adjacent unit and thus maintain the general uniformity of total results.

Fig. 4 shows the same general arrangement for record production as shown in Fig. 1 except that here the several output circuits 10 from the amplifying units, go to electromagnetic devices 20, one for each individual unit, these devices vibrating the several record cutting needles 21, to cut the record grooves G, G¹, G², etc. Also, in this case, I show each record groove, each record proper, being made on a separate record disk B. Although the several record grooves in this arrangement could of course be cut alongside each other on a single record blank, it might not be possible in such an arrangement to obtain

a suitable length of record on a single carrier. Fig. 4 therefore illustrates not only the application of my system to a mechanical record, but also illustrates the arrangement of the several records on separate carriers. And in a system such as shown in Fig. 4, the electromagnetic devices 20, may also preferably be designed and constructed so as to respond, like the other elements of the several units, with uniform high efficiency throughout their respective pitch ranges; and they may furthermore be designed and constructed so as to be relatively non-responsive to sounds outside their respective pitch ranges. The details of such designing are known and need no extended exposition here.

In Fig. 5 I show a system of reproduction corresponding to the system of record making at Fig. 4. Here the several record blanks or carriers B with their sound record grooves G, G¹, etc., are illustrated, each groove being followed by the needle 26 of the magnetic pick-up 25. The several magnetic pick-ups are connected into the input circuits of the several amplifying units A, etc., as before described, and the output circuits 10 go to several speakers H, H¹, etc., the same as in Fig. 3. The final results are, in general, the same as results before described.

In Fig. 6 I indicate how my system may be used for the production of multiplex records from a single ordinary record. As I have described before, a part of the difficulties overcome by this invention reside in the reproduction of records. In other words, a well made single sound record, although it has not the perfection of my multiplex record, still has in it such sound representations that, if they can be faithfully and fully reproduced, will give improved results. This I can do by applying my multiplex system to such a record. For instance, in Fig. 6 let B⁵ represent an ordinary phonograph record with its single sound-groove G⁵. The magnetic pick-up 25a will in this case be one that will respond as well as possible throughout the whole audible range. From this magnetic pick-up a circuit 30 with branch circuits 31 may lead to the several initial transformers L of the amplifying units A, A¹, A², etc., which may be the same as before described in all of their characteristics. Then the output circuits 10 of several amplifying units may go either to microphones, as in Figs. 3 and 5, or they may go to electromagnetic recording devices 20 operated to cut individual record grooves G, G¹, etc., in several different record blanks B; in other words, the output circuits 10 may go to any kind of sound wave producing mechanism. In one case, the final sounds are immediately produced; in the other case the sound waves are transcribed upon individual records which may then be reproduced in the manners hereinbefore described.

115
120
125
130

I claim:

The method of producing sound records, that includes making by selection from an original complete sound record of sound waves over the entire audible frequency range, a plurality of sound records each having a record of sound waves within a substantially exclusive allotted frequency band, the several records together covering the entire range of audible frequencies, and being adapted for simultaneous individual reproduction.

In witness that I claim the foregoing I have hereunto subscribed my name this 12th day of September, 1927.

15 ROY J. POMEROY.
